UNITED STATES PATENT OFFICE.

HOWARD M. P. MURPHY, OF PITTSBURGH, PENNSYLVANIA, ASSIGNOR TO THE WESTINGHOUSE AIR BRAKE COMPANY, OF WILMERDING, PENNSYLVANIA, A CORPORATION OF PENNSYLVANIA.

AUTOMATIC TRAIN-BRAKE-CONTROL APPARATUS.

1,104,823.

Specification of Letters Patent.

Patented July 28, 1914.

Application filed August 5, 1907. Serial No. 387,182.

To all whom it may concern:

Be it known that I, HOWARD M. P. MURPHY, a citizen of the United States, residing at Pittsburgh, in the county of Allegheny and State of Pennsylvania, have invented new and useful Improvements in Automatic Train-Brake-Control Apparatus, of which the following is a specification.

This invention relates to automatic train 10 brake control apparatus, and particularly to apparatus of this character wherein fluid pressure brakes are adapted to be automatically applied by the operation of mechanism on the train, which is in turn set into operation by a trip mechanism located along the line of way.

An apparatus of the above nature is disclosed in a prior application, Serial No. 373,243, and comprises, broadly stated, a 20 valve device normally subject to fluid under pressure and a trip actuated means for varying the pressure on one side of said valve device to actuate the same and thereby effect a reduction in train pipe pressure to produce 25 an application of the brakes. In this construction two such valve devices may be employed, one adapted to effect a gradual and the other a sudden reduction in train pipe pressure to produce, respectively, a service 30 and an emergency application of the brakes, each valve device being governed by separate trip devices located along the track, and one or the other being set into operation, according to the degree of danger existing as 35 the train passes said trip devices.

In the construction above referred to means are provided whereby the admission of fluid under pressure to the train pipe, by manipulation of the engineer's brake valve, 40 is prevented, while the automatic control apparatus is in its active position, so that the brakes cannot then be released by the engineer. Another feature consists in means adapted to automatically release the brakes 45 at a predetermined period of time after an automatic trip governed application of the brakes is effected.

The principal object of my invention is to provide an improved automatic train brake 50 control apparatus having the above mentioned features, wherein a single valve device is employed for effecting a service and

an emergency application of the brakes, thereby providing a compact construction of few parts.

In the accompanying drawings, Figure 1 is a diagrammatic view of an automatic train brake control apparatus with my improvements applied; Fig. 2 a central sectional view of the automatic train brake control valve device, showing the parts in normal position; Fig. 3 a similar view, showing the parts in service application position, and the valve for governing the reduction in train pipe pressure in position to regulate the release of fluid from the train pipe; Fig. 4 a similar view with the parts in service position, but showing the service reduction valve in full open position; Fig. 5 a similar view, showing the parts in the emergency application position; Figs. 6, 7 and 8 are central sectional views of a slightly modified form of valve device for automatically controlling the brakes, showing the parts respectively in normal, service application and emergency application positions.

The apparatus shown diagrammatically in Fig. 1, comprises a train pipe 1, engineer's brake valve 2, connected by pipe 3 directly, and by pipe 4 through a reducing valve 5, with the main reservoir, as heretofore, an automatic train brake control valve device 6, through which communication is normally established from train pipe 1, through pipe 7 to the brake valve to permit control of the brakes by manipulation of the engineer's brake valve 2. The usual equalizing reservoir 8 is also connected, normally, with the engineer's brake valve, through said valve device by way of pipe 9. The apparatus 90 also comprises a trip governed vent valve device 10, connected by pipe 11 with the valve device 6 and adapted to actuate said valve device to effect a service application of the brakes, a similar vent valve device 12, connected by pipe 13 with the valve device 6, for actuating said valve device to effect an emergency application of the brakes, and a time reservoir 14 connected to said valve device by pipe 15.

According to the construction illustrated in Figs. 2 to 5 inclusive, the automatic valve device comprises a casing 16 having a valve chamber 17, containing slide valve 18, and a

piston chamber 19 containing a piston 20 for actuating the slide valve 18.

The piston 20 is normally maintained in an intermediate position in the piston chamber 19 by a resistance spring 21, which may be arranged within the piston stem 22 of said piston and tends to maintain oppositely arranged stems or stops 23 and 24 in an outward position, the stems being of such length that each contacts with an adjacent wall of the casing 16, when the piston 20 is in its normal intermediate position, so that movement of said piston in either direction compresses the spring 21.

15 In the normal position, as shown in Fig. 2, the train pipe is in open communication with the brake valve through the pipe 7 and valve chamber 17, the port 25 to the brake valve side of pipe 7 registering with a port 26 in the slide valve 18, opening into said valve chamber, and port 27, to the train pipe 7, being uncovered by said slide valve 18. The equalizing reservoir 8 is also open to the brake valve, the ports 28 and 29, 20 leading respectively to the equalizing reservoir and brake valve sides of the pipe 9, being connected by cavity 30 in the main valve 18. Consequently the brakes may normally be controlled by the engineer through manipulation of the engineer's brake valve in the usual way.

When air is supplied to the pipe 7 by the engineer's brake valve, it flows through pipe 7, port 25, port 26 in the slide valve 18 to the valve chamber 17, and thence through port 27 to the train pipe side of pipe 7 charging the train pipe to the standard pressure. Air also flows through a small port 31 and a passage 32 to the inner side 40 of the piston 20, and through a passage 33 in the piston stem 22 to the spring chamber containing the spring 21, and thence through a passage 34 in the spring stop 24 to the outer side of the piston 20, so that the opposite sides of said piston are normally maintained at train pipe pressure.

The equalizing reservoir is charged in the usual way, to the normal train pipe pressure, through pipe 9, port 29, cavity 30 in the slide valve 18, port 28, to equalizing reservoir side of pipe 9 and the equalizing reservoir 8. Pipe 9 and the equalizing reservoir are also connected by a passage 35 with the outer face of an abutment 36 for regulating the rate of reduction in train pipe pressure in service applications of the brakes.

Time reservoir 14 is connected by pipe 15 60 to a port 37 in the slide valve seat, which, in normal position, registers with cavity 38 therein. A passage 39, through said slide valve 18, opens into the cavity 38, and in normal position, registers with an exhaust port 40, opening to exhaust cavity 41, so

that normally the time reservoir is at atmospheric pressure.

A close fitting piston 42 is provided on the piston stem 22, intermediate the piston chamber 19 and the valve chamber 17, so that there will be no tendency for the piston 20 to move under variations in train pipe pressure as effected by the usual movement of the engineer's brake valve, the only communication to the piston being by way of the restricted port 31.

The trip vent valve devices 10 and 12 may be of any desired construction, for venting fluid from one side of the piston 20, when actuated by the track trip, but I prefer to employ a trip vent valve device similar to that shown and described in the prior application Serial No. 373243 hereinbefore referred to, wherein the vent valve is maintained in open position, after actuation, for a predetermined period of time, so as to insure a sufficient venting of fluid from the piston.

Upon actuation of the service vent valve device 10, by a track trip, fluid under pressure is vented from the chamber at the outer face of the piston 20, so that the higher pressure on the inner face of said piston shifts the same to its extreme outer position, the stem 24 compressing the spring 21. The slide valve 18 thereupon assumes the position, as shown in Fig. 3, in which the port 25 to the brake valve side of pipe 7 is closed, so that the train pipe is cut off from the engineer's brake valve, preventing the release of the brakes during the time the piston 20 and valve 18 are in this position. Port 27 leading to the train pipe side of pipe 7 is now open to the exhaust by way of valve chamber 17, port 43, passage 44, port 45, in the slide valve seat, cavity 46 in the slide valve 18 to the exhaust port 41. Air is thus exhausted from the train pipe to produce an application of the brakes. In order to effect a gradual reduction in train pipe pressure to a predetermined degree, to thereby produce a service application of the brakes, the time reservoir 14 is employed, and in this position, communicates with the equalizing reservoir 8. The port 37, leading to pipe 15 and the time reservoir 14, being connected, by cavity 38 in the valve 18, with port 28 leading to pipe 9 and the equalizing reservoir 8. Air flows from the equalizing reservoir into the time reservoir, and also to the outer side of said piston 20, until equalization of pressures has been effected, and in the meantime the train pipe pressure is being reduced through exhaust port 41, and correspondingly on the inner side of the piston 20.

As soon as the train pipe pressure on the inner face is reduced substantially to equal the fluid pressure on the outer side of the piston, the spring 21 exerts sufficient pressure to return the pis- 130

ton and valve to the normal position, closing the train pipe exhaust, and opening communication from the brake valve through pipe 7 to the train pipe whereby 5 air is then supplied to the train pipe, automatically releasing the brakes. It will be noted that when the piston 20 is in its outer position, the stem 24 shifts inwardly, relative to piston 20, closing the port 34 therein, 10 to prevent flow of air from the train pipe to passage 47 and the reservoirs. But in order to prevent air which might possibly leak around the stem 24 from flowing to passage 47 and the reservoirs, I preferably provide 15 a seating ring 55 on the piston 20, to effectively shut off communication. Upon the return of the valve 18 to normal position, the time reservoir is again connected to the exhaust port 41 through passage 40, and 20 the equalizing reservoir with pipe 9, leading to the brake valve, so that control of the brakes is again restored to the engineer.

On short trains the fluid pressure in the train pipe reduces more rapidly than on 25 long trains, and in order to secure a more uniform rate of reduction in train pipe pressure, I provide means for regulating the size of the opening, through which the fluid from the train pipe flows to the exhaust 30 port. Such means may preferably consist of an abutment 36, contained in a chamber 49 of a cap 73, which may be secured to the valve chamber end of the casing 16. The abutment 36 operates a stem 51, adapted on 35 forward movement to restrict an opening 43 connecting the valve chamber 17 with the passage 44, leading to the exhaust. A spring 52 tends to maintain the abutment 36 against its seat 53, and the abutment is subject on 40 its outer face to the fluid pressure of the equalizing reservoir, to which it is open through the passage 35. The inner face of the abutment is open, through a passage 50, to the valve chamber 17 and the train pipe.

45 It will now be apparent, that should the train pipe pressure reduce more rapidly than the equalizing reservoir pressure, the latter pressure will shift the abutment inwardly and the stem 51 will correspondingly restrict the opening 43, from the train pipe to the exhaust port, as shown in Fig. 3, thereby regulating the rate of exhaust of fluid pressure from the train pipe. If the train pipe reduction proceeds at a rate relatively the 50 same as the rate of reduction in the equalizing reservoir pressure, as would be the case on long trains, the abutment remains in its outer position, as shown in Fig. 4.

When the emergency vent valve 12 is actuated, fluid under pressure is vented from the inner face of the piston 20, by way of the passage 32, causing the piston 20 to shift the valve 18 inwardly, assuming the 55 position as shown in Fig. 5, in which the spring 21 is compressed by the action of the

stem 23. The cavity 46 then connects the port 27 to the pipe 7, leading to train pipe, with the wide open exhaust port 41 and the train pipe pressure is thereupon rapidly reduced, to effect an emergency application of 70 the brakes. The brake valve communication with the train pipe is closed through port 25 by the slide valve 18, as in a service application, so that the engineer cannot release the brakes, or prevent the normal operation 75 of the automatic valve device.

The time reservoir is connected through port 37, cavity 38, and passage 57 with passage 32 and the inner face of the piston 20, and the equalizing reservoir is open to the 80 valve chamber 17 by way of port 28 which registers with through port 58, in this position. Fluid under pressure thus flows from the equalizing reservoir into the valve chamber 17 and thence gradually equalizes 85 through the small port 31 and the passage 32, into the time reservoir and on the inner face of the piston 20, the fluid under pressure also flows from the valve chamber 17 through the port 33 to the spring chamber 90 of spring 21 and thence through port 34 to the chamber 19 and outer face of piston 20. The port 33 and passage 34 are large compared with the port 31, so that the pressure on the outer face of the piston rises more 95 rapidly than on the inner face thereof and consequently the piston remains in its inner position, until the fluid flowing through the small port 31 and around the piston 42 has substantially equalized with the pressure on 100 the outer face, then the piston 20 and valve 18 are returned to normal position by the action of the spring 21. The piston 20 is preferably provided with an inner seating ring 60, to prevent the possible leakage of 105 fluid past the piston 42, to the passage 32 and the time reservoir, so that the only flow will be through the restricted port 31, on the size of which will then depend the period of time during which the piston remains in its emergency position. As hereinbefore described, the train pipe is again connected with the engineer's brake valve and the time reservoir with the exhaust, and brakes are automatically released, upon return of the piston 110 to its normal position.

A modified construction is shown in Figs. 6 to 8 inclusive, wherein the main valve 18 and piston 20 are substantially the same in construction and operation as described in 120 connection with Figs. 2 to 5 inclusive. If desired, independent springs 61 and 62 may be employed with stops or stems 63 and 64 respectively, tending to maintain said piston and valve in their normal position. In this 125 construction, an additional exhaust port 65 is provided, which is uncovered upon movement of the valve 18 and piston 20 to service position. The exhaust passage 66 leading from the exhaust port 65, is provided with 130

a check valve 67, which may be adjusted according to the degree of reduction in train pipe pressure desired, as for example, at a standard train pipe pressure of 70 pounds, 5 the spring 68 may be adjusted to 55 pounds, thereby permitting a train pipe reduction of 15 pounds in service applications of the brakes. The operation of the apparatus in 10 service applications is otherwise the same as before described, as also the emergency action, the equalizing port opening to the outer face of the piston, being the passage 70 instead of by way of the spring stem, as in the first described construction.

15 A passage 71 may be provided to connect the portion of pipe 7 leading to the brake valve with the train pipe side of said pipe. The passage 71 contains a check valve 72 facing toward the brake valve. With this 20 arrangement, a reduction in train pipe pressure may be made by the engineer's brake valve to effect an application of the brakes, regardless of the position of the automatic valve device, but the brakes cannot be released by reason of the check valve 72, which 25 prevents flow of air to the train pipe.

It will now be apparent that I have provided a compact construction, wherein a 30 single valve device is adapted to govern both service and emergency applications of the brakes when set into action by the operation of a track trip device.

Having now described my invention, what 35 I claim as new and desire to secure by Letters Patent is:—

1. An automatic train brake control apparatus comprising a valve device having a normal position and movable in one direction from the normal position to effect 40 a gradual reduction in train pipe pressure and produce a service application of the brakes and movable in the opposite direction from the normal position to effect a sudden reduction in train pipe pressure and produce 45 an emergency application of the brakes, and means for automatically actuating said valve device.

2. An automatic train brake control apparatus comprising a valve adapted to effect 50 a gradual reduction in one position and a sudden reduction in train pipe pressure in another position, upon movement to either position from an independent normal position, to thereby produce respectively a service 55 and an emergency application of the brakes, a piston for actuating said valve and means for automatically operating said piston.

3. An automatic train brake control apparatus comprising a valve adapted to effect 60 a gradual reduction in one position and a sudden reduction in train pipe pressure in another position, upon movement to either position from an intermediate normal position,

65 to thereby produce respectively, a service and an emergency application of the brakes, a piston, normally subject to opposing fluid pressures for actuating said valve, and an automatically operated valve for varying the pressure on one side of said piston to actuate the same.

4. An automatic train brake control apparatus comprising a valve and actuating piston therefor, normally subject to opposing fluid pressures, a vent valve adapted to 75 vent fluid from one side of said piston to actuate said valve, to effect a gradual reduction in train pipe pressure and produce a service application of the brakes, and another vent valve adapted to release fluid 80 from the opposite side of said piston to actuate said valve to effect a sudden reduction in train pipe pressure and produce an emergency application of the brakes.

5. An automatic train brake control apparatus comprising a valve device, means 85 for actuating said valve device to thereby effect a gradual reduction in train pipe pressure in one position and a sudden reduction in another, and a yielding resistance 90 means for returning said valve device to an intermediate position.

6. An automatic train brake control apparatus comprising a valve device, subject 95 on one side to fluid at train pipe pressure, means for actuating said valve device to open a train pipe exhaust port, a reservoir normally at train pipe pressure and means for reducing the pressure therein and for connecting the same to the opposite side of 100 the valve device to actuate said valve device and close said train pipe exhaust port upon a predetermined reduction in train pipe pressure.

7. An automatic train brake control apparatus comprising a valve, an actuating piston, subject on one side to train pipe pressure, means for actuating said piston and valve to open a train pipe exhaust port, an equalizing reservoir normally containing 110 fluid at train pipe pressure, a reservoir normally at atmospheric pressure adapted to be connected to said equalizing reservoir and to the opposite side of said piston to actuate 115 said piston and valve and close said exhaust port upon substantial equalization of fluid pressures on said piston.

8. An automatic train brake control apparatus comprising a valve, an actuating piston, subject on one side to train pipe pressure, means for actuating said piston and valve to open a train pipe exhaust port, an equalizing reservoir normally containing 120 fluid at train pipe pressure, a reservoir normally at atmospheric pressure, adapted to be connected to said equalizing reservoir 125 and to the opposite side of said piston and yielding resistance means for returning said

piston and valve to close said exhaust port upon reduction of the train pipe pressure to substantially equal that on the opposite side of the piston.

5 9. An automatic train brake control apparatus comprising a valve device, means for actuating said valve device to open a train pipe exhaust port and means for regulating the flow of fluid through said exhaust port, 0 and a piston, subject to the opposing pres-

sures of the train pipe and the flow of fluid from a regulating chamber, for actuating said regulating means.

In testimony whereof I have hereunto set my hand.

HOWARD M. P. MURPHY.
